UNITED STATES PATENT OFFICE.

SAMUEL HAYWARD, OF BOSTON, MASSACHUSETTS, ASSIGNOR TO J. ESTEY & CO., OF BRATTLEBOROUGH, VERMONT.

DESIGN FOR REED-ORGAN CASES.

Specification forming part of Design No. 7,843, dated November 3, 1874; application filed September 14, 1874.
[Term of Patent 14 years.]

CASE C.

To all whom it may concern:

Be it known that I, SAMUEL HAYWARD, of Boston, Massachusetts, have invented a Design for an Organ-Case, and assigned to J. ESTEY & Co., of Brattleborough, Vermont, of which the following is a specification:

The nature of my design is fully represented in the annexed photographic illustration, to which reference is made.

The ends of the case are designed in a plain rectangular form, the top and bottom being ornamented with a double band of molding, as shown. The general surface of the end is plain or flat, as represented, but is relieved and ornamented by two narrow panels, *a a*, arranged centrally on the end, and extending nearly the entire length of the case. The ends of the case are adorned by projecting ornamental handles, which are situated in the usual position on the ends, and are formed of three projecting cubical knobs, *c c c*, which are arranged on the relieved portion of the ends, one at the center, and one at each side. The cubes are united by a rounded transverse bar, *b b*, extending from one to the other, which is ornamented with turned rings at its connections with the cubes. The top of the front corners of the case is formed with a "line of beauty" curve, as shown at *k*, and at the end of the curve is formed an ornamental knob, *d*. The curved top rests upon a console, *e*, which emerges a short distance below the key-board, and terminates in a foliated base, which rests on the projecting corner of the base of the instrument. The music-rack *f* is composed of a series of horizontal parallel bars, separated from each other by a narrow space, and joined by two or more transverse bands, *g g*, as shown. The front of the key-

board is formed to correspond with the design of the music-rack, by being ornamented with a series of longitudinal parallel grooves or slots, as shown at *i*, and the lower edge of the front is ornamented by a bold projecting molding, *h*, extending entirely across the front, and terminating abruptly at the consoles *e e*. The front board *l* of the case is adorned by a panel, *n*, whose vertical sides are embraced by vertical bars *p*, rising from the inverted brackets *o o*. The bars are tapered toward each end, and formed into a rectangular enlargement at the center, as shown. A medallion, *m*, is formed on the center of the panel, and from it extends the horizontal bar *r*, which unites with the vertical bars *p p*, as shown.

I claim as my invention—

1. The design for the handle of an organ-case, formed of the cubical knobs *c c c* and cylindrical bar *b b*, substantially as shown and described.

2. The design for the front corners of an organ case, composed of the curved top *k*, in combination with the console *e*, substantially as shown and described.

3. The design for a music-rack of an organ-case, composed of longitudinal bars, joined by transverse bands, substantially as herein shown.

4. The design for the front of an organ, formed of the medallion *m*, with the bars *r r p p*, as set forth.

In witness whereof I have hereunto signed my name in the presence of two subscribing witnesses.

SAMUEL HAYWARD.
